PLUG CATCHER AND INDICATOR

Thomas M. Ragan, Downey, Calif., assignor to
 Baker Oil Tools, Inc., Vernon, Calif., a corpo-
 ration of California

Application July 25, 1946, Serial No. 686,087

11 Claims. (Cl. 166—1)

1

This invention relates to well tools, and more particularly to subsurface apparatus especially useful in the sealing of wells with cement slurry, liquid synthetic resins and other cementitious materials.

In the tubing method of cement wells, it is desirable to know when the charge of cementitious material has reached, or has been ejected from, the tubing string, in order that the proper amount of displacement fluid may be pumped into the tubing on top of the sealing material to insure its discharge in the required amount into the well bore. Measurement of the displacement fluid alone does not give assurance that the proper amount of sealing material has been ejected from the tubing string, in view of the lack of knowledge of the exact cubic contents of the tubing string running to the top of the well bore. Reliance solely upon such measurements frequently results in the pumping of insufficient sealing material from the tubing, or results in forcing of all of the sealing material and some of the undesired displacement fluid into the well bore.

Accordingly, it is an object of the present invention to provide an improved apparatus for giving a positive indication of the location of the cementitious material in the tubing string or well bore.

A further object of the invention is to provide an improved plug catcher adapted to form part of a tubing string, capable of providing a positive indication that the plug has reached the location of the catcher in the tubing string, and of permitting circulation in both directions around the tubing plug without fear of inadvertently shutting off or restricting such circulation.

A further object of the invention is to provide a catcher for a tubing plug of relatively simple construction, and which prevents the plug from preventing flow of fluid in either an upward or downward direction through the catcher and tubing string.

Still a further object of the invention is to provide a catcher for a tubing plug of simple and economical construction, which may be readily assembled and dismantled for cleaning and maintenance purposes.

This invention has other objects which will become apparent from a consideration of the embodiments shown in the drawings accompanying and forming part of the present specification. These forms will now be described in detail to illustrate the general principles of the invention, but it is to be understood that such detailed description is not to be taken in a limited sense.

2

since the scope of the invention is best defined by the claims appended hereto.

Referring to the drawings:

Figure 1 is a longitudinal section through one form of apparatus embodying the invention disposed in a well casing;

Figure 2 is a view similar to Figure 1 with parts in a second operative position;

Figure 3 is a view similar to Figure 1 with parts in still another operative position;

Figure 4 is a longitudinal section through a modified form of invention disposed in a well casing;

Figure 5 is a view similar to Figure 4 with parts in another position of operation; and

Figure 6 is a cross-section taken along the line 6—6 in Figure 2.

The plug catcher includes an upper sub 10 adapted for threaded connection to a joint of tubing 11 forming part of a tubular string running to the top of the well bore. A depending cylindrical sleeve 12 is threadedly secured on the sub 10 to provide an enlarged chamber for a tubing plug 13 pumped down the tubing string in leakproof engagement with its interior wall or surface. A lower sub 14 is threaded in the lower end of the cylinder or chamber, forming the lower portion of the plug catcher.

The upper sub 10 has a depending tubular guide extension 15 extending into the chamber 12, provided with a plurality of outwardly opening circulation ports or passages 16. The lower end 17 of the guide is tapered downwardly and inwardly, while the lower sub 14 has a plurality of spaced upwardly extending supporting fingers 18 having upwardly and inwardly inclined tapered portions 19. The distance between the lower end 17 of the guide tube 15 and the upper ends 19 of the supporting fingers is substantially greater than the length of the tubing plug 13 to be pumped down the tubing string and into the plug catcher chamber 12.

The guide tube 15 contains a plug seat 20 held in position above the circulation passages 16 by one or more frangible pins or shear screws 21. This seat has an upwardly and inwardly inclined tapered seating surface 22.

Although various suitable designs of tubing plugs may be used in conjunction with the plug catcher, the one illustrated in the drawings is an elongate plug of rubber or rubber-like material capable of being pumped or squeezed through restrictions or passages of substantially less diameter than the normally unrestrained diameter of the plug. This plug has peripheral lip seals 23

facing in both an upward and downward direction for efficient slidable sealing contact with the tubing wall while being pumped downward through the tubing string. The normal unrestrained diameter of the plug 13 is substantially equal to the inside diameter of the tubing string 11, and may be of a slightly greater diameter to insure the effective sealing action of its lips 23 against the tubing wall.

In the form of invention disclosed in Figures 1, 10 2, 3 and 6, the guide tube 15 has an inside diameter substantially less than the outside diameter of the tubing plug 13, whereas the inside diameter of the plug catcher chamber 12 is substantially greater than the outside diameter of the tubing 15 plug 13.

The lower end of the plug catcher is shown, for purposes of illustrating one representative use of the device, as being threaded into a tubular supporting member 24 of a packer, to which is secured a downwardly facing cup-shaped packing or swab cup 25 sealing against the wall of a casing 26 having perforations 27 through which cementitious material is to be pumped. It is to be understood, however, that the plug catcher may be used alone, or in conjunction with apparatus other than the packer specifically illustrated.

Let it be assumed that a charge of cement slurry is to be pumped down the tubing string 11 for passage through the casing perforations 27 to form a cementitious seal around the exterior of the casing 26. The tubing plug 13 is placed in the tubing string at the lower end of the charge of cement slurry, and the cement slurry with the plug preceding it is pumped down through the tubing string by displacement fluid on top of the slurry. A top cementing plug 28 may or may not be placed on top of the charge of cement slurry to separate it from the displacement fluid, as desired.

The plug or plugs 13, 28 and cement slurry are pumped down the tubing string 11 until the plug 13 reaches the upper sub 10 of the plug catcher. Since the guide tube 15 depending from the upper sub has a much smaller diameter than the plug 13, the pressure on the fluid in the tubing string 11 must be increased to squeeze the plug into the guide tube. This rise in pressure affords an indication at the top of the well bore that the slurry has reached the plug catcher. The plug 13 comes to rest on the upper end 22 of the seat, with the downwardly diverging tapered surfaces 29 on the end of the plug engaging the corresponding tapered upper surface on the seat 20, to insure against squeezing of the plug through the central passage in the seat. Such engagement of the plug 13 with the seat 20 requires that the pressure on the fluids in the tubing be increased quite substantially before the shear screws 21 are disrupted, to enable such fluids to blow the plug 13 and seat 20 downwardly out of the guide tube 15 and into the enlarged plug catcher chamber 12.

The rise in pressure required to shear the screws 21 also advises the operator that the lower end of the cement slurry has reached the plug catcher, and the drop in pressure following shearing of the screws and pumping of the plug and seat into the enlarged chamber 12 indicates to the operator that the cement slurry is being pumped through the plug catcher, flowing through the chamber 12 around the plug 13, and between the fingers 18 (on which the seat 20 and plug 13 have come to rest) into the central

5 the packer body 24, for discharge from the latter device, from where it passes outwardly of the casing 26 through its perforations 27. The packer cup 25 engages the casing wall above its perforations to force the cement slurry to pursue a path through the perforations 27.

The required amount of cement slurry may be pumped out of the apparatus, as by measurement determination, or, if a top cementing plug 28 is employed, the operator is advised when the top cementing plug reaches the plug catcher by the rise in pressure accompanying its attempt to squeeze into the restricted plug passage 15a through the upper sub 10 and its depending guide tube 15.

Following the placement of the required quantity of cement slurry behind the casing, any excess slurry that may remain in the tubing string 11, plug catcher 10, 12, 14, or lower packer device 24, 25 may be pumped from the tubing string by reverse circulation; that is, by pumping downwardly through the annulus around the tubing string 11, the circulating fluid flowing down past the exterior of the packing cup 25 and up through the packer into the lower sub 14, from where it passes through the circulation passage between the supporting fingers 18 into the chamber 12, flowing around the tubing plug 13 and into the guide tube passage 15a, either through its lower end or circulating ports 16. The excess cement slurry and circulating or washing fluid proceeds up through the restricted plug passage 15a in the upper sub 10 and continues through the tubing string 11 to the top of the well bore.

In the event that there is any tendency for the reversely circulating washing fluid to elevate the tubing plug 13 towards the guide tube 15, the reverse fluid flow cannot be arrested by closing of the restricted guide tube passage 15a by the tubing plug, since the tapered surface 30 on the upper end of the latter merely engage the correspondingly tapered surface 17 at the lower end of the guide tube, the circulating fluid passing upwardly around the plug 13 and into the guide tube through the circulating ports or passages 16. Pumping of the plug into the central tube passage 15a is prevented, because its normal unrestrained diameter is substantially greater than the inside diameter of the central plug passage 15a, the upward and outward inclination of the tapered surfaces 30, 17 on the plug and guide tube tending to flare the plug outwardly, rather than pressing it inwardly into a position allowing its upward squeezing into the restricted plug passage.

In order to hold the tubing plug 13 in a generally central position within the chamber 12, to insure uniform flow of fluid around the plug, both while pumping cement slurry or other fluids down through the tubing string or during the reverse circulating of fluids, spaced longitudinally extending guide and centering ribs 31 may be secured to the interior of the chamber, as by welding material 32, the inner surfaces of the guide ribs 31 being positioned greater in radial extent from the axis of the chamber 12 than the radius of the tubing plug 13. These guiding or centering ribs prevent material inclination of the plug in the chamber and insure its remaining in a vertical position substantially coaxial of the chamber, so that fluid may flow readily around the plug 13 and between the ribs 31.

In the form of invention just described, provision is made for obtaining two different pres-

sure indications; one due to the added pressure required to squeeze the plug 13 downwardly into the restricted plug passage 15a in the upper sub 10, and the second due to the necessity for shearing the screws 21, of predetermined shear value. If desired, the plug seat 20 and screws 21 may be omitted from the guide tube 15 and the pressure indication obtained only as a result of squeezing the plug into and through the restricted passage 15a.

The plug 13 is prevented from being pumped down through the chamber 12 to a position closing the lower sub central passage 14a by engagement of its lower downwardly diverging surface 29 with the corresponding inclined seating surfaces 19 at the upper ends of the supporting fingers 18. Since the passage 14a through the lower sub 14 is substantially less in diameter than the normal unrestrained diameter of the tubing plug 13, the latter cannot be pumped into the passage, its lower downwardly divergent surface 29 engaging the inclined surfaces 19 on the fingers, which tend to stretch the plug outwardly, and thus preclude its movement into the lower sub passage 14a. In this manner, assurance is had that the plug is prevented from closing the outlet end of the plug catcher.

In the form of invention disclosed in Figures 4 and 5, the passage 33 through the upper sub 10 is substantially the same in diameter as the inside diameter of the tubular string 11 to which it is attached. Reliance is not had upon a restricted passage to give a rise in pressure indication upon entry of the plug 13 into the upper sub. Instead, sole reliance is placed on the plug seat 20 initially secured to the guide tube by the shear screw 21. Also, in this form of invention, the centering ribs 31 are omitted. In all respects, however, the plug catcher arrangement functions in substantially the same manner as the specific plug catcher disclosed in the other form of the invention, and has substantially the same advantages.

The plug catcher may be readily dismantled and reassembled, simply by unscrewing the upper and lower subs 10, 14 from the cylinder 12, which permits removal of the plug 13, allows all parts to be readily cleaned, and facilitates replacement of the plug seat 20 and shear screws 21 in the depending guide tube 15. Reassembly takes place by again threading the upper and lower subs 10, 14 into the plug catcher cylinder or chamber 12.

It is, accordingly, apparent that a plug catcher has been devised which provides a positive indication at the top of the well bore that the plug has reached the location of the catcher in the tubing string. The plug catcher arrangement entraps the tubing plug and insures against its prevention of downward or upward flow of fluid through the apparatus. The device is economical to manufacture and maintain.

Although specific reference has been made to the entrapment of a bottom tubing plug 13 in the plug catcher, it is to be understood that it could also be used to entrap a top tubing plug 28. The charge of cement slurry may be pumped down the tubing string without a bottom tubing plug, but with a top tubing plug separating the cement slurry from the following displacement fluid. The operator at the top of the well bore is advised of the fact that all of the cement slurry has been pumped into or through the plug catcher by squeezing of the top plug 28 into the restricted passage 15a in the upper sub 10, or by

its engagement with the plug seat 20. The increase in pressure in the fluid above this plug 28 then shears the screws 21 or squeezes it through the restricted passage into the enlarged chamber 12, permitting reverse circulation to take place to clear any excess cement slurry from the apparatus within the well casing. If desired, pumping may stop upon engagement of the top tubing plug with the plug seat 20 and reverse circulation employed to pump the top tubing plug 28 in a reverse direction back through the tubing 11 to the top of the well bore, followed by the excess cement slurry and washing fluid.

While I have described several forms of my invention, what I claim and desire to secure by Letters Patent is:

1. A device of the character described connectable to a tubular string through which a flexible plug may be pumped, including a tubular chamber larger than said plug to permit bypassing of fluid therearound when said plug is positioned in said chamber, a tube projecting into the upper end of said chamber and having means at its lower end engageable with the upper end of said plug to prevent upward pumping of said plug from said chamber, and means in the lower end of said chamber and engageable with said plug to prevent downward passage of said plug from said chamber.

2. A device of the character described connectable to a tubular string through which a flexible plug may be pumped, including a tubular chamber larger than said plug to permit bypassing of fluid therearound when said plug is positioned in said chamber, a tube projecting into the upper end of said chamber and having means at its lower end engageable with said plug to prevent upward pumping of said plug from said chamber, a seat releasably secured to said tube to arrest downward movement of said plug through said tube, and means extending into the lower end of said chamber and engageable with said seat, when said seat is released from said tube, to prevent downward passage of said plug from said chamber.

3. A device of the character described connectable to a tubular string through which a flexible plug may be pumped, including a tubular chamber larger than said plug to permit bypassing of fluid therearound when said plug is positioned in said chamber, a tube projecting into the upper end of said chamber and having a central passage smaller in diameter than the outside diameter of said plug, the lower end of said tube being engageable with said plug when said plug is positioned in said chamber to prevent upward movement of said plug from said chamber, said tube having a passage through its sidewall permitting flow of fluid between said chamber and the central passage of said tube when said plug is in engagement with the lower end of said tube.

4. A device of the character described connectable to a tubular string through which a flexible plug may be pumped, including a tubular chamber larger than said plug to permit bypassing of fluid therearound when said plug is positioned in said chamber, a tube projecting into the upper end of said chamber and having a central passage smaller in diameter than the outside diameter of said plug, the lower end of said tube being engageable with said plug when said plug is positioned in said chamber to prevent upward movement of said plug from said chamber, said tube having a passage through its wall permit-

ting flow of fluid between said chamber and the central passage of said tube when said plug is in engagement with the lower end of said tube, and means in the lower end of said chamber engageable with said plug to prevent downward movement of said plug from said chamber.

5. A device of the character described connectable to a tubular string through which a flexible plug may be pumped, including a tubular chamber larger than said plug to permit bypassing of fluid therearound when said plug is positioned in said chamber, a tube projecting into the upper end of said chamber having a central passage smaller in diameter than the outside diameter of said plug, the lower end of said tube being engageable with said plug when said plug is positioned in said chamber to prevent upward movement of said plug from said chamber, said tube having a passage through its wall permitting flow of fluid between said chamber and the central passage of said tube when said plug is in engagement with the lower end of said tube, a seat releasably secured to said tube above said wall passage to arrest downward movement of said plug through said tube, and means in the lower end of said chamber engageable with said seat to prevent downward movement of said plug from said chamber.

6. A device of the character described connectable to a tubular string through which a flexible plug may be pumped, including a tubular chamber larger than said plug to permit bypassing of fluid therearound when said plug is positioned in said chamber, a tube projecting into the upper end of said chamber having a central passage smaller in diameter than the outside diameter of said plug, the lower end of said tube being engageable with said plug when said plug is positioned in said chamber to prevent upward movement of said plug from said chamber, said tube having a passage through its wall permitting flow of fluid between said chamber and the central passage of said tube when said plug is in engagement with the lower end of said tube, a seat releasably secured to said tube above said wall passage to arrest downward movement of said plug through said tube, means in the lower end of said chamber engageable with said seat to prevent downward movement of said plug from said chamber, and spaced longitudinally extending ribs in said chamber for substantially centering said plug therein.

7. A device of the character described, including an upper sub connectable to a tubular string through which a flexible plug may be pumped, a tubular chamber detachably secured to said upper sub, a lower sub detachably secured to said chamber, a tube depending from said upper sub and having a passage through its wall, means extending upwardly from said lower sub and having a passage through its wall, said chamber being larger in diameter than said plug and the distance between said tube and upwardly extending means being greater than the length of said plug.

8. A device of the character described, including an upper sub connectable to a tubular string through which a flexible plug may be pumped, a tubular chamber detachably secured to said upper sub, a lower sub detachably secured to said chamber, a tube depending from said upper sub and having a central passage smaller in diameter than the outside diameter of said plug and also having a passage through its wall, means extending upwardly from said lower sub and having a passage through its wall, said chamber being larger in diameter than said plug and the distance between said tube and upwardly extending means being greater than the length of said plug.

9. A device of the character described, including an upper sub connectable to a tubular string through which a flexible plug may be pumped, a tubular chamber detachably secured to said upper sub, a lower sub detachably secured to said chamber, a tube depending from said upper sub and having a central passage smaller in diameter than the outside diameter of said plug and also having a passage through its wall, the end of said tube tapering downwardly and inwardly, means extending upwardly from said lower sub and having a passage through its wall, the upper end of said means tapering upwardly and inwardly, said chamber being larger in diameter than said plug and the distance between said tube and upwardly extending means being greater than the length of said plug.

10. A device of the character described connectable to a tubular string through which a flexible plug may be pumped, including a tube adapted to be attached to said tubular string for receiving said plug, a tubular chamber larger than said plug secured to said tube, said tube projecting into said chamber in spaced relation to the inner wall of said chamber, said tube having a passage through its wall opening into said chamber, and a seat secured in said tube above said passage.

11. A device of the character described connectable to a tubular string through which a flexible plug may be pumped, including a tube adapted to be attached to said tubular string for receiving said plug, a tubular chamber larger than said plug secured to said tube, said tube projecting into said chamber in spaced relation to the inner wall of said chamber, said tube having a passage through its wall opening into said chamber, a seat secured in said tube above said passage, and frangible means securing said seat to said tube.
